ROTARY VANE PUMP

John Stewart Wilcox, Inglewood, Calif., assignor
to Technical Instrument Laboratory, Ingle-
wood, Calif., a copartnership

Application June 11, 1946, Serial No. 676,035

2 Claims. (Cl. 103—120)

1

My invention relates to pumps of the vane type and more particularly to a pump of this type employing rollers as vane elements.

The pump of my invention includes many improvements over previous designs to render it more efficient and cheaper to manufacture. It includes the use of improved rollers, improved rotors, improved cavity forms, improved variable cavities, novel sealing means, improved flow control mechanisms, improved end plates and improved assembly construction. These improvements are combined in the pump which will be described producing an overall improvement in pump performance as well as providing new pump design and constructions.

It is, therefore, an object of the invention to provide a vane-type pump, wherein the pump cavity is of a selected design for efficient and long lasting operation.

Another object of the invention is to provide a vane-type pump having a contact point between the rotor and casing formed of a separate plate that is formed in a true arc.

Still another object is to provide a roller-type vane pump having improved roller construction.

Still another object of the invention is to provide a pump cavity of improved construction, which produces improved results as either a constant capacity or variable capacity pump.

A further object is to provide a vane pump with end plates which are automatically adjustable to bear against the rotor with a pressure proportional to the pressure developed within the pump.

Another object of the invention is to provide a vane-type pump in which the entire pump assembly is secured together by a locking ring.

Another object of the invention is to provide a vane pump in which the direction of flow of output is unaffected by the direction of rotation of the rotor.

Another object of the invention is to provide an outlet fluid mixing apparatus employing a single variable capacity vane pump.

Other objects and advantages of my invention will be apparent from the following description and claims which may best be understood by reference to the appended drawings forming a part of the specification, in which:

Fig. 1 is an elevation side view of the pump 50 of my invention;

Fig. 2 is an elevation front view of the pump as indicated by the lines II—II of Fig. 1;

Fig. 3 is a partial vertical section through the pump of Fig. 1 as indicated by the line III—III of Fig. 2;

Fig. 4 is a transverse section through the pump along the line IV—IV of Fig. 3;

Fig. 5 is a partial sectional view through the pump along the line V—V of Fig. 4;

2

Fig. 6 is a sectional view of the pump housing alone taken along the line VI—VI of Fig. 4;

Fig. 7 is a partial sectional view of the pump housing and the end plate assembly and is taken 5 along the line VII—VII of Fig. 4;

Fig. 8 is an elevation view of the cavity ring of the pump also shown in Fig. 4;

Fig. 9 is a sectional view of the cavity ring taken along the line IX—IX of Fig. 8;

Fig. 10 is a perspective view of the spider insertable in the cavity ring for varying the capacity of the pump;

Fig. 11 is a perspective view of a stationary 10 part of an end plate assembly of the pump;

Fig. 12 is a perspective view of the adjustable portion of the end plate assembly, adapted to be inserted in the part of Fig. 11 by rotation about a vertical axis of 180°;

Fig. 13 is a view through the adjustable end 15 plate portion of Fig. 12 taken along the line XIII—XIII of Fig. 12;

Fig. 14 shows a modified form of roller for use in the invention comprising a metal rod coated with rubber-like material;

Fig. 15 shows a second modification of roller 20 for use in the invention, including articulated end pieces;

Fig. 16 shows a third modification of roller for employment in the invention consisting of 25 vane elements drilled to receive a roller that projects slightly from the outer surface of the vane;

Fig. 17 is an application of the pump of the 30 invention in a fluid mixing arrangement wherein variable proportions of the mixed fluids may be obtained;

Fig. 18 is a schematic illustration of a pump 35 housing and cavity ring that are employed when a constant direction of flow of output is desired, regardless of the direction of rotation of the rotor of the pump;

Fig. 19 is a perspective view of one of the arc 40 blocks employed to define the pump cavity;

Fig. 20 is a detail sectional view of a portion of the spider shown in Fig. 10 taken along the plane XX—XX of Fig. 10;

Fig. 21 is a perspective view partly in section 45 of a modified form of pump roller having resilient ends;

Fig. 22 is a perspective view of a modified form of magnetizable pump roller;

Fig. 23 is a fragmentary view of a pump rotor showing an idler roller assisting a conventional roller in a rotor slot;

Fig. 24 is a side view of the idler rotor of 50 Fig. 23;

Fig. 25 is an axial section through a modified form of pump employing large porting area;

Fig. 26 is a view along the line XXVI—XXVI 55 of Fig. 25 showing an elevation view of the pump porting; and

Fig. 27 is a fragmentary elevation view of the rotor of Fig. 25 showing the porting within the rotor.

The general assembly of my invention, which is illustrated as a dual cavity pump is shown best in Figs. 1 through 5. Referring particularly, however, to Fig. 1, there is illustrated a generally cylindrical pump housing 20 to which is connected an inlet pipe 21 through which fluid is introduced into the pump, whereupon the pump is actuated by a drive shaft, such as shaft 22 shown in dotted outline. The output from the pump is delivered through an integrally formed boss 23, the flow being indicated by appropriate arrows.

Referring now to all of Figs. 1 through 5, it will be noted that the pump housing 20 is formed with a circular cylindrical interior 24 in which is disposed an inner end plate assembly 26, a rotor member 27, a cavity ring 28, an outer end plate 29 and a retaining ring 31 locking all of the members together within the housing 20. The rotor 27 is axially relieved at 25 into which fits a projection 38 of the face plate 29, which projection acts as a bearing for the rotor 27 in alignment with the radial thrusts exerted on the rotor by the pumped fluids.

It will be noted, particularly with reference to Fig. 4, that there is provided variable capacity members 32 in each end of the cavity ring 28 for varying the displacement of the pump, and these members will be described in more detail herein-after, particularly with reference to Fig. 10.

Also secured within the cavity ring 28 are arc blocks 33, which are accurately machined to form a leak-proof seal between adjacent pressure and intake areas of the pump, the radially curved face bearing against the rotor, spring loaded as shown in Fig. 19, if desired, to maintain seal, the back divided into two or more (three shown) sections, each section independently ported, as indicated at 33a, 33b and 33c to the adjacent section of the rotor face, so the pressure urging it against the rotor is slightly greater than the fluid pressure of the adjacent areas of the rotor, either by reason of the spring load or because any leakage of pressure will be on the rotor side of the blocks.

The rotor 27 has peripheral grooves 34 formed therein which are parallel to the axis of rotation, and in which rollers 36 are loosely retained.

The various components of the assembly shown in Figs. 1 through 5 are illustrated more clearly in Figs. 6 through 13. The porting within the pump housing 20 is shown in part in Fig. 6, the other half of the porting being in the section that is removed from that figure, and is illustrated in Fig. 4. Shown in Fig. 6, however, is a recessed portion 37 in the intermediate portion of the cylindrical cavity 24 forming one of two identical portions of the fluid inlet manifold. In the lower part of Fig. 6 is shown a similar cavity 38 which is one of two identical parts of the fluid outlet manifolds, the recess 38 being connected by cast passageways 39 within the housing 20 to an outlet formed in the integral boss 23 to which any desired conduit may be attached.

The initial portion of the fluid inlet manifold is shown in Fig. 7, wherein it will be noted that the outer end plate 29 has integrally formed therein, preferably by casting, passageways 41 which also appear in dotted outline in Fig. 2. The inlet manifolding is continued within the cavity ring 28.

The cavity ring 28 is best illustrated in Figs. 75

8 and 9, wherein it will be noted that there are four radial slots formed therein, two opposed slots 42 acting as terminal portions of the inlet manifold and the two other opposed slots 43 acting as initial portions of the outlet manifold. Further with reference to Figs. 8 and 9, it will be noted that the cavity ring 28 has external shoulders formed on the interior thereof near the various ports as indicated at 44. These shoulders 44 form the portions upon which the spider assembly 32 (Fig. 10) rests, and rectangular relieved portions 46 in the spider ring accommodate the enlarged base of the spider 32. The rollers 36, however, normally contact curved interior portions 45 of the cavity ring 28.

Thus, by reference to Figs. 7, 8 and 9, it will be apparent that the inlet to the pump includes the passageways 41 in the outer end plate 29, the relieved portions 37 in the pump housing 20 and the slotted passages 42 in the cavity ring 28.

The outlet manifold connections on the other hand are best shown with reference to Figs. 5 and 6, fluid flowing through the slots 43 in the cavity ring 28, thence into the relieved portions 38 on the interior of the pump housing 20, and through the passageways 39 to the outlet boss 23.

As mentioned previously, my invention includes improved means for varying the working cavity volume of the pump, and this function is performed by the two spiders 32 shown best in Fig. 10. In that figure it will be seen that there is a solid rectangular base 47 having a groove 48 formed about the perimeter thereof and adapted to receive a sealing ring 49 best shown in Fig. 3. Projecting from the rectangular base 47 along the two opposite edges are curved legs 51 of rectangular cross-section that are adapted to rest in the shoulders 44 formed in the cavity ring 28, as previously described. The rectangular base 47 of the spider 32 fits within the rectangular recesses 46 of the ring 28 which has been described previously with reference to Fig. 8.

It will be noted from an inspection of Figs. 3 and 5 that the interior end plate 26 has fitted therein a separate plate 52 formed particularly in accordance with my invention. The end plate 26 is shown best in Fig. 11 wherein it will be observed that the interior of one face is recessed in oblong fashion at 53 with deeper recesses 54 formed from the approximate position of the minor axis to the approximate position of the major axis, including sufficient area to be equal or greater than the adjacent pressure area of the rotor. The recessing operation leaves an internal flange 56. The adjustable member 52 fitting within the inner end plate 26 is shown in Fig. 12 and there it will be noted that this member has two raised portions 57 of a size and shape corresponding to the two relieved portions 54 of greatest depth of the member 26 of Fig. 11. Further, these raised portions 57 are provided with perimetric grooves 58 adapted to receive a sealing ring 59 best shown in Figs. 3 and 5. The member 52 is drilled through the two raised portions 57 as at 60, allowing fluid under pressure to act equally on both sides of the raised portions 57. The assembly of the two pieces of Figs. 11 and 12 is indicated in Figs. 3 and 5 and is performed by rotating the member of Fig. 12 about a vertical axis so that the two raised portions 57 are opposite to the more deeply recessed portions 54 of Fig. 11 and the two are then pressed together forming the end plate assembly together with the sealing ring 59.

Referring now to general features of design,

particularly with reference to Fig. 4, it will be noted that the curved interior portions 45 of the cavity ring 28 make a smooth contact with the arc block inserts 33. This contact is of special design in accordance with my invention and embodies the use of a parabolic or a semi-elliptical or other smooth curve that is initially tangent to the true circle of the arc blocks 33, and all parts of the curve lie on or inside of all tangents to the curve between the junctions of the arcs of the blocks 33 and the curve between them. This permits a true circular pressure seal at the blocks 33 without an angular break in contour such that would cause the rollers or vanes to jump, vibrate or pound such as is present in other pumps. In this connection, it should be noted also that the arc blocks 33 may be formed with extreme accuracy and appropriately hardened and thereafter inserted in the cavity ring 28, thus facilitating construction of this part of the pump wherein highest accuracy is required.

Other features of interest are shown also in Figs. 3 and 4 and include seals for the outer end plate 29 in the form of an elastic ring 61. The rotor 27 has its shaft portion 62 sealed within the housing 20 by a sealing means 63. In connection with all the seals illustrated, it should be noted that these may be of the type commonly employed in hydraulic equipment wherein the annular seal has a circular cross-section, the diameter of which in its free condition is slightly in excess of its groove depth in which it is placed, resulting in an initial compression when assembled. When liquid thereafter contacts these seals, they are further compressed against one edge of the groove, this fluid pressure still more effectively causing the ring to seal against leakage.

Further with reference to Figs. 3 and 4, it will be noted that the pump housing 20 is drilled at 64, which drill hole communicates with a similar hole 65 in the cavity ring in the region of the rectangular recess 46. These two holes permit the use of a mechanical actuator to urge the spider 32 toward the rotor or, alternatively, to admit fluid pressure which urges the spider 32 toward the rotor. This fluid under pressure may be obtained by tapping the output of the pump, as indicated by the conduit 66 as shown in dotted outline in Fig. 3.

Further with reference to Figs. 3 and 5, it will be noted that the rollers 36 are centrally recessed at each end as at 35. This eliminates the rounded wear of rollers which is otherwise encountered and thereby eliminates the tendency of such a rounded roller to bind in the pump cavity or to leak about its rounded end. The wear on the ends of the rollers approximates a lapping action, and it is well known that a ring will lap flat or planar, whereas the end of a cylinder laps to a convex surface.

The operation will be described with reference to Figs. 1 through 5. Power is applied by the shaft 22 splined onto the rotor stub shaft 62, causing the rotor 27 as a whole to rotate, for example, in the direction of the arrow indicated in Fig. 4. Fluid then flows from the conduit 21 into the interior of the end plate 29 to passages 41 (Fig. 2), and thence into recesses 37 (Fig. 4), through the cavity ring slots 42 as shown in dotted outline in Fig. 4. The rollers 36 are thrown outwardly by centrifugal force and are rolled on the inner circular edges 45 of the cavity ring 28. As the rollers leave the arc block plates 33, the volume between two successive rollers gradually increases, reaching a maximum at the

end portions of the oval-shaped cavity, at which point the rollers are contacting the central solid portion of the spider 32. Thus, during this travel from the arc blocks 33 to the central spider portion 32, fluid is being induced into the rotor region by suction and is carried across the solid portion of the spider 32. Thereafter, when the rotation is from the center of the spider 32 to the arc blocks 33, the cavities between successive rollers gradually decrease, thereby expelling liquid or fluid from the rotor region and driving it outwardly to form the high pressure output of the pump. Thus, the fluid is driven outwardly through the slots 43 in the cavity ring 28 into the relieved portion 38 of the housing 20, and thence through the passages 39 to the outlet boss 23.

The contact with the arc blocks 33 is extremely exact due to the close machining of the insert 33 and the contact of the cavity ring surfaces 45 with the arc blocks 33 is smooth, being tangential to the terminal edge of the arc block 33. The contact of the rollers with the surface 45 and the arc blocks 33 is rolling, reducing friction and wear to a minimum on these rolling contact surfaces, thus increasing efficiency and life of the pump as a whole.

When it is desired to vary the output of either or both cavities of the pump, a mechanical operator or hydraulic fluid under pressure is admitted to the passage 64 in the housing 20 and in passing through the cavity ring hole 65 acts on the outer end of the spider 32, forcing it inwardly. This reduces the allowable maximum of the cavities formed between successive rollers and thus reduces the output of the pump for a given rotational speed.

Referring particularly to Fig. 5, it will be noted that the inner end plate 26 retains the movable member 52 having the drilled passage 60 communicating the high pressure region of the pump (as indicated by the output connection) with the interior or right-hand face of the insert 52. Thus, the pressure of the pump is transmitted to the back of the plate 52, causing it to float, and by making the area of the plate 52 slightly in excess of the working area of the output cavities of the pump, a slight force can be exerted by the plate 52 toward the rotor and its rollers, thus maintaining an automatically adjustable compression contact with the rotor, reducing leakage. If desired, light springs may be interposed behind plate 52 to maintain the seal when the pump is at rest.

Various modifications of the rollers 36 of the invention are shown in Figs. 14, 15 and 16. Fig. 14 illustrates a roller having a metal core 67 coated with a rubber-like material, such as neoprene, and is particularly useful in pumps that handle gritty substances that cause pitting of the metal rollers.

Fig. 15 shows a metal roller having a central portion 69 with rounded ends on which are disposed end caps 70 having an internal socket to fit over the rounded ends of the portion 69. This articulated roller unit is designed to allow for angular motion of the end members without scoring the ends of the case, accommodating slight angular movements that occur particularly on the starting and stopping.

Fig. 16 shows vanes 71 within rotor slots 72, the vanes being drilled to receive rollers 73 that project through the upper surface of the vanes 71. The vanes 71 substantially fill the slots 72 and thus eliminate voids in the rotor as it passes the arc blocks 33, making this structure particu-

larly adaptable for pumping gases, though for pumping liquids, it may be desirable to relieve the slots as is later described with reference to Fig. 27. Further, with reference to Fig. 16, it will be noted that the outer surface 74 of the vanes is curved so as to conform closely to the radius of the rotor surface, but to clear a cavity surface, insuring the contact line will be the roller itself, thus facilitating the close contact of the vane element with stator walls, further reducing any voids that might be present.

Fig. 17 illustrates an application of my variable capacity pump for use as a fluid mixer. This is based upon the fact that the vane pumps are positive displacement pumps and when two or more separate outputs are joined in one conduit, mixing in exact ratios or proportions is obtained. In that figure is illustrated a pump casing 75 in which are placed two variable cavity members 76 having stems 77 that project radially outward through the casing. Inlet pipes 78 and 79 introduce the two different fluids to the pump casing 75 and when the pump is actuated (rotating parts are not shown), fluid is delivered to two outlet pipes 81 and 82 joined together at 83 where they are mixed in the exact proportions desired. The two variable cavity members 76 are operated independently or together by means of lever arms 83 pin jointed to ears 84 integrally formed on the casing 75. The outer ends of the lever arms 83 are pin jointed to internally threaded collars 85 having a common threaded shaft 86 passing therethrough. Secured to a center part of the shaft 86 is an annulus 87 engaged by two bushing nuts 88 threaded into a fixed member 89 secured to the pump casing 75. Thus, the shaft 86 as a whole may be moved one way or the other to change the settings of the two variable members 76 and in addition the shaft 86 may be manually rotated as by the link 90 to change the proportions of the fluids. By selecting the pitch of the threads for each end of shaft 86, either alike or different, any combination of uniform or differential adjustment of the two cavities may be obtained.

Illustrated in Fig. 18 is a modification of my pump structure wherein the cavity ring is rotatable within limits instead of fixed. A pump casing 91 has inlets and outlets indicated by the arrows for direction of flow and has placed within its circular interior a cavity ring 92 of corresponding circular outside shape. A pin 93 is secured to the cavity ring 92 and engages a stop pin 94 near an outlet port and the cavity 92 as a whole may be rotated counter-clockwise 90° to engage a second stop pin 95. It will be noted that this 90° rotation will shift the delivery ports of the cavity ring 92 90° with respect to the fixed pump casing 91. Therefore, when the direction of rotation of a rotor (not shown) is changed, the frictional engagement of the rotor with the cavity ring 92 will cause it to rotate in the new direction of travel, thus shifting the ports. Due to the fact that a change of rotation of travel reverses the flow of fluid through the ports, the rotation of the cavity ring corrects for this reversal, causing the new flow to be delivered out the same ports as the prior flow. Thus, is obtained a uniform direction of flow through the pump casing regardless of the direction of rotation of the rotor. This mechanism is particularly useful on lathes, rolling mills, etc. wherein the pump may be used as a lubrication pump driven by the main machinery which is being frequently

reversed in direction, while the lubrication flow and direction remain constant.

On the other hand, the direction of fluid delivery may be reversed without reversing the direction of rotation of the rotor by positively moving the stator between its limits of motion by means of any suitable moving device diagrammatically indicated in Fig. 8 as a handle 96.

Provision of the movable end plate 52 described particularly with reference to Figs. 11 and 12 is also used as a means for compensating for wear of the rotor face and the roller ends, as well as providing a seal that is proportional to the working pressure. As the adjustable end plate 52 moves toward the rotor to compensate for wear in the rotor, it would tend to interfere with the spider section 32 and the arc block sections 33. In this connection it will be noted that except for the guide surfaces 45, the legs 51 of the spider member 32 and the edges of the arc blocks 33 form substantially the entire peripheral edge portions of the entire cavity in which the rotor 27 operates. Accordingly I provide means for allowing the movable end plate 52 to move toward the spiders 32 and the arc blocks 33 in the form of interlocking grooves.

Shown particularly in Fig. 12 are milled notches 97 on the outer edge of the adjustable end plate 52, which edge will contact the spider 32 and the arc blocks 33 when the entire end plate 52 is rotated to fit within the stationary end plate 26 of Fig. 11 as previously explained. Likewise, the spider members 32 have their legs 51 adjacent to the end plate 52 notched at 98 as shown in Figs. 10 and 20. These notches 98 are preferably made with milling cuts and are parallel to the direction of movement of the entire spider 32. The notches 98 leave raised portions 98a between them, which raised portions 98a are so positioned with respect to the end plate 52 that they are positioned opposite the grooves 97 of the end plate 52, the grooves 97 being cut parallel to the notches 98. The arc block members 33 likewise have milled notches 99 formed parallel to their direction of movement and the raised portions 99a between the notches match corresponding grooves 97 in the end plate 52. Therefore, when wear occurs on the axially transverse face of the rotor 27 and on the ends of the rollers 36, the pressure biased end plate 52 may move toward the rotor 27 without hindrance since the notches previously mentioned are complementary and interlock. This construction of notches therefore permits the end plate 52 to not only maintain a pressure responsive sealing engagement with the rotor, but also permits it to compensate for wear. The notches are preferably much smaller than the width of the webs between the rotor slots and may be about half as wide as the diameter of the rollers. In connection with Fig. 19 the arc blocks 33 may be urged toward the rotor 27 by means of a spring 30a.

Shown in Fig. 21 is a modified form of pump roller 101 having projecting pegs 102 on each end. Bonded to each end and covering the pegs 102 is a cap 103 of rubber-like material such as neoprene. This structure results in the entire end portions of the roller being resilient and there is little tendency for the end cap 103 to wear if the roller 101 gets out of axial alignment with the rotor. Also in the pumping of gritty substances, the particles which would normally cause a wearing action tend to depress the rubber momentarily and roll along its surface until the particle is clear of the roller. Thus instead of a grinding action which induces wear, a rolling relatively non-

wearing action is produced at the ends of the roller.

Shown in Fig. 22 is a roller 104 made of magnetically permeable material such as hard steel or steel metal alloys and made into a simple permanent magnet. When this roller 104 is used in connection with a ferrous cavity ring 28 and a non-ferrous rotor 27, it clings to the cavity ring 28. The cavity ring may be magnetized and the roller made of magnetizable material to accomplish the same result. This roller is therefore highly desirable for pumps operated at very low rotational speeds or pumps that must have a positive displacement upon initial rotation without any lost output. This type of roller is also highly desirable in adapting the construction for use as a fluid motor.

Shown in Figs. 23 and 24 is a rotor construction employing an idler roller to insure that the main roller will be thrust outwardly. A rotor segment 106 has an axial peripheral groove 107 therein in which is placed a solid cylindrical main roller 108 and a smaller idler roller 109 having its central portion relieved. When the rotor 106 moves in the direction of its arrow, the main roller 108 will contact the inner edge of the arc cavity (not shown) and rotate in the direction indicated by its arrow. The main roller 108 contacting the idler roller 109 will cause the idler roller 109 to rotate in the direction of its arrow causing the idler roller 109 to tend to climb out of the groove 107. This action tends to push the roller 108 outwardly and into very secure engagement with an arc cavity in which it is used. This arrangement of rollers is very desirable with extremely viscous fluids.

Shown in Figs. 25, 26 and 27 in a modified form of the invention wherein an extremely large porting area is obtained relative to the pumping volume. A pump casing is formed of two portions, a rear portion 111 and a front portion 112. The front portion 112 has an inlet opening 113 and an outlet opening 114. Positioned within the housing parts is a rotor 116 having a bearing within the rear housing portion 111. The inlet and outlet ports are symmetrical and introduce and receive liquid or fluid at four separate points to the rotor 116; namely, at the outer periphery, at the ends of the rollers, at the edges of the rotor, and at the bottom of the rotor slots. The left half 112 of the housing is shown in Fig. 26 and it will be noted that the four inlet portions include an outer opening 117 and concentric semi-circular slots 118, 119 and 120. The outlet has corresponding slots 122, 123, 124 and the main outlet opening 126, all corresponding to the four porting areas mentioned previously. A common manifold 127 connects the four inlet areas and a common manifold 128 connects the four outlet areas. The rear housing portion 111 is similarly formed.

Referring to Figs. 25 and 27, it will be noted that the rotor construction includes axial peripheral slots 129 in which are disposed rollers 131. Further, the forward or left portion of the rotor 116 contains a plurality of axial recesses 132 near the axis of the rotor each communicating with the center portion of the roller slot 129 by means of a radial passage 133. The bottoms of the slots 129 toward each rotor face are angularly recessed as at 134. The innermost semi-circular inlet port 126 supplies fluid to the passages 132 and 133 which supply fluid to the center portion of the slot 129. The intermediate port 119 supplies fluid to the tapered portions 134 of the slot supplying fluid to the slot at the edges. The outermost semi-circular port 118 supplies fluid

to the slots 129 at the ends of the rollers 131 and the main inlet port 117 supplies fluid peripherally to the rotor.

By means of the large porting area shown in Figs. 25, 26 and 27, my pump is enabled to operate at extremely high speeds without cavitation. Further, it permits the use of a roller-type vane pump for extremely viscous fluids such as liquid asphalt which have heretofore been beyond the capabilities of vane-type pumps.

I prefer to use roller-type vanes in my pumps because they eliminate pulsations in the output of the pump as compared to normal vane pumps. This is due to the fact that in normal vane pumps, the vane represents a "dead" volume which results in the non-uniformity of fluid output. In the roller-type vane, however, as the roller is depressed down within its groove, it displaces liquid from this groove, ejecting it into the outlet of the pump and thereby maintaining the outlet delivery uniform. This lack of pulsation and general smoothness of operation of pumps made according to my invention permit the use of extremely high speed pumps that can operate satisfactorily on speeds in the range of 40,000 to 50,000 R. P. M. These high rotational speeds are especially desirable in association with turbine type equipment such as exhaust gas supercharger turbines or the conventional hot air or jet turbines, allowing direct coupling of the fuel pumps, lubrication pumps, etc. to the main shaft.

While I have described by invention with reference to particular embodiments thereof, it is evident that the invention is equally applicable to other types of pumps; for example, I have shown dual cavity pumps, but the invention disclosed herein is equally applicable to single cavity or any other numbered cavity pumps. Also, I have shown my invention as applied to a single cavity pump, but it is readily apparent to those skilled in the art that the invention is applicable to pumps of any number of cavities. Likewise, the invention may be usefully employed in a fluid motor and is not therefore restricted to pumps.

It will be noted also with respect to Fig. 4 that the slots 34 of the rotor 27 have non-parallel sides and further are flared outwardly in excess of a radial direction. These angular side walls make it impossible to jam the roller in the slot and the pump is very tolerant of dirt and other foreign matter. The outward flare in excess of a radial direction also tends to urge the rollers more securely in contact with the cavity wall. Additionally, the slot is much easier to machine than one with parallel walls because it may be easily milled or hobbed on standard gear cutting equipment.

While I have described what is at present considered to be the preferred embodiments of my invention, it will be understood that various modifications may be made therein, and it is intended to cover in the appended claims all such modifications as fall within the true spirit and scope of my invention.

65 I claim:

1. In a pump, a housing having a circular cylindrical cavity open at one end and having a concentric smaller aperture at the other, a circular rotor disposed within the housing having a shaft on one side concentric to the cavity and projecting through the aperture for a driving connection, said rotor having a cylindrical cavity on the other side concentric to the cavity in the housing, a circular end plate closing the open end of the cylindrical cavity of the housing and

11

having an integral concentric projection on the inner surface thereof which fits within the rotor cavity to act as a bearing for the rotor, the end plate being free of any shaft aperture, and lock means for securing the end plate to the housing.

2. In a pump, a housing having a circular cylindrical cavity open at one end and having a concentric smaller aperture in the other, a generally circular cup shaped rotor disposed therein having a shaft on one side projecting through the aperture for a driving connection and having a cavity in the other side concentric to the housing cavity, a circular end plate fitting in the housing cavity and having an integral projection on the inner side thereof which fits within the rotor cavity to act as a bearing, the end plate being free of any shaft aperture, said end plate having a central recess on the outer side thereof, and lock means for securing the end plate in the housing.

JOHN STEWART WILCOX.
